UNITED STATES PATENT OFFICE.

JOHN B. BAXTER, OF WATERVLIET, NEW YORK, ASSIGNOR TO COVERT MANUFACTURING COMPANY, OF WATERVLIET, NEW YORK, A CORPORATION OF NEW YORK.

PIVOTED-TONGUE SNAP-HOOK.

1,109,390.

Specification of Letters Patent. Patented Sept. 1, 1914.

Application filed December 20, 1910. Serial No. 598,348.

To all whom it may concern:

Be it known that I, JOHN B. BAXTER, a citizen of the United States, residing at Watervliet, in the county of Albany and 5 State of New York, have invented certain new and useful Improvements in Pivoted-Tongue Snap-Hooks, of which the following is a specification, reference being had therein to the accompanying drawing.

10 This invention relates to improvements in pivoted tongue snap hooks and consists in certain novel features of construction, and in the peculiar arrangement and combination of its parts, as will be fully herein- 15 after described, and defined in the claims.

The invention has more particularly to deal with pivoted tongue hooks wherein a 20 spring is utilized for retaining the tongue in locking engagement with the hook proper, and the improvements include novel means 25 of connection for the several parts, comprising the hook, tongue, and spring, whereby the device is easy to manufacture, and is rendered more durable and efficient in operation, and whereby the parts are more readily coupled together, while permitting of their detachment, as desired.

In the accompanying drawings forming a 30 part hereof, I have shown convenient embodiments of the invention, for the purpose of illustration, and in the said drawings, Figure 1 is a bottom plan view of the snap hook, Figs. 2 and 3 are longitudinal and transverse sectional views respectively, 35 Figs. 4 and 5 are detail views of a modified form of tongue, Figs. 6 and 7 are detail views of still another modified form of tongue, Figs. 8, 9 and 10 are detail views of still another modified construction of 40 tongue.

With more particular reference to the drawings, like reference numerals designate corresponding parts throughout the several views, in which 1 is the body portion of 45 the hook, the same having at one end an inwardly and upwardly curved part 2, constituting the hook proper, and conveniently terminating at its rear end in a loop part 3 adapted for the reception of a link or other 50 attaching member. The forward wall 3^a of the loop member may be said to constitute a closed end for the body portion of the hook, which said forward wall is conveniently extended upwardly, as shown, above 55 the upper surface of the body portion of

the hook, and forming a shoulder against which a portion of the tongue member, presently to be described, engages when in normal position. Arranged forwardly of said shoulder 3^a is a transversely extending slot 60 4 in the body portion of the hook, the transversely extending wall 4^a constituting a pivotal bearing for the tongue member. The under surface of the body portion 1 is reduced at said bearing part, as indicated in 65 Fig. 2, the said reduced portion connecting with the opening 4 extending through said body portion. It is obvious, of course, that the bearing 4^a, which for convenience may be termed a bearing bar, may be formed by 70 placing a bar in the body portion of the hook at a point intermediate the ends of the opening 4. However, the preferred construction resides in forming said bearing bar integral with the body portion of the 75 hook.

The tongue member comprises an elongated body portion 5 adapted at its forward end to engage within the reduced part 2^a of the hook terminal, and having projecting 80 downwardly from its sides adjacent its said forward end, suitable ears 6, which if the tongue is stamped from sheet metal, may be formed by bending down the projecting sides of the tongue sheet. The tongue is 85 preferably widened toward its rear end, as shown at 7, and said widened part has a downwardly extending upright wall 8 of a width to overlie the ends of the slot 4 and rest upon the upper surface of the body portion of the hook at a point immediately adjacent the shoulder 3^a. The upright portion 8 of the tongue is conveniently of a height in excess to that of the shoulder 3^a, 90 whereby to facilitate the operation of the tongue, and to protect the fingers of the operator when the device is in use. Projecting downwardly from the upright portion 8 of the tongue is a tail or lip 9 adapted to be curved about the bearing bar 4^a and rest 100 within the plane of the outer surface of said body part 1.

The spring member is preferably U-shaped comprising an elongated bearing arm 10 adapted to engage the inner surface of the 105 tongue and rest between the downwardly projecting side ears 6 of the latter, and having a heel part 11 adapted to rest in the recess formed by the opening 4 of the body portion 1 of the hook, and which said 110

heel portion of the spring has a downwardly projecting engaging part, conveniently a bent terminal 12 adapted to engage behind a shoulder 13 and rest in a recess 14 in the body portion 1 of the hook. Said shoulder 13 may be said to constitute means for limiting the longitudinal play of the spring, as is obvious. Either the bearing rod 4^a, or the tail 9 of the tongue may be provided with a recess therein of a width slightly in excess of the width of the spring member at the bend 15 thereof, but preferably both of said parts are provided with a recess, that in the bar 4^a being indicated by the reference numeral 4^b, and that in the tail of the tongue by the reference numeral 9^a. The spring at its bend is mounted upon the bearing bar 4^a at said recessed part 4^b, and beneath the tongue at said recess 9^a. In the application of the parts, the spring is conveniently placed upon the bearing bar and in engagement behind the shoulder 13, as is obvious, when the tongue is applied with its recessed part overlying the bend of the spring, and if the tongue is formed of sheet metal as is preferred, the tail thereof upon being inserted through the slot 4 is bent about the bearing bar 4^a. The recessed parts 4^b and 9^a in the bearing bar and tongue respectively prevent any undue binding or contacting action between the spring and the tongue, in the operation of the latter. Projecting downwardly from the tongue are oppositely disposed lugs or projections 15', one on each side of the spring member, and preferably of a length to overlie both arms of the spring. These arms constitute guides for the spring, and prevent unnecessary lateral play of the latter, and they are conveniently of bendable metal and adapted to be bent or curved to constitute with the tail 9 of the tongue about the bearing bar 4^a, as shown, whereby a substantially continuous or closed pivotal bearing engaging about the rod 4^b.

In Figs. 4, 5, 6 and 7 is shown a slightly modified form of construction in which the forward wall 3^a of the loop part of the device is reduced at 16 to constitute the bearing rod or bar for the tongue. In this embodiment of the invention, the body portion of the hook is provided with an opening 17 forwardly of said bearing bar, and the tongue is preferably formed of a single sheet of metal with the tail 18 thereof slotted to form one or more bendable lips or lugs 19 to pass through the opening 17 in the body portion of the hook and engage around the bearing bar 16 in a direction opposite to that of the body portion of the tail 18 which passes rearwardly about said bearing bar. The body portion of said tail of the tongue constitutes in effect a continuation of the wall of the shoulder 3^a, since the same when in

position will be substantially flush with the outer surface of said wall, as shown. In applying the parts the spring is first applied to the bearing bar as before, when the body portion of the tail of the tongue will be bent rearwardly about the bearing bar, and the slotted lugs of the tongue bent forwardly about the bearing bar, and preferably overlapping the terminal of the body portion so as to constitute a substantially closed bearing to engage the bearing bar.

In that embodiment of the invention illustrated in Figs. 8, 9 and 10, the forward wall 3^a of the loop is substantially flush with the body portion 1, and the tongue 20 when in position rests at its rear end 20^a upon said wall 3^a. The body portion 1 of the hook is provided with an opening 21 separated by a transversely extending bearing bar 22, and projecting downwardly from the inner surface of the tongue are two pairs of lugs, conveniently of bendable metal, said lugs being arranged one pair upon each side of the spring. One lug of each pair is arranged to bend or curve about the bearing bar forwardly of the latter, and the other lug of each pair is adapted to be curved or bent about said bearing bar rearwardly of the latter, as is clear, and the respective lugs of each pair constituting a substantially continuous bearing extending around the bearing rod, and lying within the plane of the outer surface of the body portion 1, as shown.

In each of the embodiments, it will be appreciated that the bearing point for the tongue is adjacent to and preferably is the same bearing point for the bend of the spring with the result that the spring is more efficient in operation, and the retaining action thereof more readily overcome in the operation of the tongue. Again, the construction is very advantageous where a short hook is desired, the improvements being equally applicable to hooks of various sizes. It will also be observed that the particular connection for the tongue constitutes an effective retaining means for the latter, since a substantially closed bearing is provided, and also a part or parts of said bearing constitute in effect a housing or guide engaging over the sides of both arms of the spring and preventing any undue lateral play of the latter. Should it be desired to separate the parts, it is only necessary to rebend the tail of the tongue and the cooperating oppositely disposed lugs or projections, when the tongue may be readily lifted from engagement with the body portion of the hook, and when the spring will be free for removal, as is obvious.

Having thus described the invention, what I claim as new and desire to secure by Letters Patent is:

1. In a snap hook, a body part having a

hook at one end, and a transversely extending bearing bar at its opposite end, a substantially U-shaped spring mounted at its bend on said bearing and engaging at one end the hook member and at its opposite end the tongue, the tongue being formed of bendable material and having a tail piece bent about and under the bearing bar, and also having integral elongated flat fingers 10 projecting at a point intermediate its sides, one finger being at each side of the spring with the flat surface thereof bent forwardly of and under the bar.

2. In a snap hook, a body portion having at one end a hook, and adjacent its opposite end a bearing member, a tongue, and a bent spring, said spring engaging at its bend the said bearing, the tongue having a bent part projecting over the bearing member, the 20 bearing part and tongue having oppositely disposed recessed portions in which the bend of the spring lies, and the inner surface of the bent portion of the tongue at opposite sides of its recess being relatively wide and 25 adapted to engage the bearing member.

3. In a snap hook, the combination of a body part having a hook at its forward end and a transversely extending bearing bar adjacent its opposite end said bearing bar 30 being separated intermediate its ends from the body part of the hook, a tongue adapted at its forward end to engage the hook, a substantially U-shaped spring mounted at

its bend on said bar with one arm engaging the body part and one arm engaging the 35 tongue, the said tongue having intermediate its sides a downwardly projecting relatively wide rearwardly extending tail portion adapted to engage over the rear surface of the bar and overlying the spring, and said tongue also having intermediate its sides separated downwardly projecting relatively 40 wide flat lugs, one at each side of the spring arms, the flat surface of the said lugs engaging about the forward surface of the bar. 45

4. In a snap hook, the combination of a body part, a hook part, a bearing part on the body part, a tongue adapted at its free end to engage the hook and having the rear end of its body part extending to form a relatively wide integral projecting tongue free from side flanges whereby its inner surface is adapted to be bent around and engage the bearing part, a substantially U-shaped spring mounted at its bend on said bearing part 50 and beneath the bent tongue of the hook, and integral projections depending from the tongue on opposite sides of the spring adjacent said bearing part. 55

In testimony whereof I affix my signature 60 in presence of two witnesses.

JOHN B. BAXTER.
